UNITED STATES PATENT OFFICE.

CHARLES W. DE LANEY, OF HAMMOND, INDIANA.

TICKET AND LABEL CABINET.

1,029,346.

Specification of Letters Patent.

Patented June 11, 1912.

Application filed July 9, 1910. Serial No. 571,144.

To all whom it may concern:

Be it known that I, CHARLES W. DE LANEY, a citizen of the United States, residing at Hammond, in the county of Lake 5 and State of Indiana, have invented certain new and useful Improvements in Ticket and Label Cabinets, of which the following is a specification.

My invention relates to new and useful 10 improvements in ticket and label cabinets and the particular object of the invention is to provide a desirable label cabinet and a novel form of guide for the tickets or labels whereby the label may be readily drawn 15 therefrom and properly positioned to be severed.

A still further object is to provide a novel 20 means of forming a tension for the guide adapted to act upon the tickets or labels so that the same may be readily and accurately severed by means of a knife of novel form 25 and pivotally carried by the guide.

The invention consists of certain other 30 arrangements and combinations of parts as will be hereinafter more fully described, it being understood that certain changes in the specific structure shown and described may be made within the scope of the claims without departing from the spirit of the invention.

In the drawings: Figure 1 is a perspective view of a cabinet partly in section to show the application of my improved guide thereto. Fig. 2 a detail view of a blank 35 adapted to form a portion of the guide, Fig. 3 is a view of a blank forming a casing portion of the guide, Fig. 4 is a detail sectional view on an enlarged scale showing the arrangement of the parts and tension spring 40 in position.

Referring to the drawing, the numeral 38 designates a suitable cabinet having the usual sliding lid 40 and a front wall 41 of a slightly greater thickness than the other 45 parts. The guide bracket 42 is secured to the front wall 41 by means of screws or the like 43 which are disposed through openings in the bracket and an extension 44 thereof, and said bracket is bifurcated to form outwardly 50 projecting arms 45 having transverse recesses 46 therein adjacent their outer ends and upon the upper faces thereof, said recesses being adapted to receive a tension spring 47 formed of a flat strip of spring 55 steel and properly held in position by means of the guide plate 48. The guide plate 48

is provided with a similar opening 19 and beveled forward edge 20 and the sides 49 are adapted to be bent downwardly and disposed against the under faces of the arm 45 60 where they are secured in any suitable manner and adapted to hold the tension spring 47 in position outwardly of the opening 19.

The guide bracket is cut at one corner, as at 37, and upon the sides 49 being bent downwardly a wing 29 is produced, said wing being formed with an aperture 28, through the medium of which the cutting blade 30 is pivotally connected by the bolt 31. The cutting blade is formed with a 70 curved cutting edge 32 so that labels may be properly severed thereby upon being fed from a roll contained in the cabinet, and when the knife is swung upwardly. The free end of the blade 30 is formed with the 75 circular head 33 for engagement by the first finger of the operator when the thumb rests upon the guide bracket.

The cabinets may be provided with a plurality of label receiving receptacles and 80 in operation the strips are wound in a reverse direction thereby permitting it to travel over the rounded surface of the guide in a more uniform manner and with less danger of catching or clogging within the 85 cabinet. It is to be further understood that the labels and guides may be made of different widths as well as the cabinet, to accord with the particular package and sizes 90 thereof, upon which the labels are to be used, and in order to insert a ticket or label through the guides it is found most desirable to trim the end thereof to a point.

It will now be seen that a guide is provided which may be conveniently attached 95 to receptacles in general as well as those constructed as described and which when provided with a cutting knife in the manner set forth, will permit the ticket or label to be severed more accurately when drawn 100 to the proper position by grasping the same through the openings 19 therein.

What is claimed is:

1. The combination with a cabinet, of a guide member projecting therefrom and 105 having depending L-shaped flanges, a bracket member having recessed furcations fitting between the depending flanges of the guide member, an undulating spring member passing transversely of the guide and 110 having its ends fitting into the recesses of the furcations of the brackets, and a cutting

blade pivoted to the guide to pass across the ends of the said guide and to cut a label projecting therefrom.

2. The combination with a cabinet, of a bracket secured to the said cabinet and having forwardly projecting furcations, said furcations each having a recess formed in the upper face thereof, a guide member secured to the cabinet and having flanges bent around the furcations of the brackets, an undulating spring member having its ends fitting into the recesses of the furcations and

having its intermediate portion bearing against the guide member to resiliently hold a label in position, and a pivotally supported blade member adapted to pass transversely of the end of the guide to sever a label projecting from the end of the guide. 15

In testimony whereof I affix my signature, in the presence of two witnesses.

CHARLES W. DE LANEY.
